UNITED STATES PATENT OFFICE.

WILLIAM F. MICHAEL, OF PHILADELPHIA, PENNSYLVANIA, ASSIGNOR TO
BAILEY, BANKS & BIDDLE, OF SAME PLACE.

DESIGN FOR A SPOON.

SPECIFICATION forming part of Design No. 21,025, dated September 1, 1891.

Application filed July 9, 1891. Serial No. 398,978. Term of patent 3½ years.

To all whom it may concern:

Be it known that I, WILLIAM F. MICHAEL, a citizen of the United States, residing in the city and county of Philadelphia, State of Pennsylvania, have invented and produced a new and original Design for a Spoon, of which the following is a specification, reference being had to the accompanying drawing, forming part thereof.

10 The leading feature of my design for a spoon is the handle thereof, having thereon the representation of a musket and a sword, the sides of which constitute in part the terminal edges of said handle.

15 In the drawing, A designates the handle of

a spoon, on which is the representation of a musket B and a sword C, the same constituting in part the terminal edges of said handle. At the tip end is shown the representation of a scroll D, and on the shank is a wreath E. 20 The tip shown in connection herewith forms no part of the design.

I claim—

A design for the handle of a spoon, as shown and described.

WILLIAM F. MICHAEL.
